UNITED STATES PATENT OFFICE.

ROCCO DELARMI, OF NEW YORK, N. Y.

DESIGN FOR AN EGG TRAY.

Application filed June 13, 1922. Serial No. 2,665. Term of patent 14 years.

To all whom it may concern:

Be it known that I, Rocco DELARMI, a citizen of the United States, residing at New York, in the county of New York and State of New York, have invented a new, original, and ornamental Design for Egg Trays, of which the following is a specification, reference being had to the accompanying drawing, forming part thereof.

The figure is a perspective view of an egg tray, showing my new design.

I claim:

The ornamental design for an egg tray, as shown.

ROCCO DELARMI.
